(57) **CLAIM**

The ornamental design for a sweatshirt with a TV watch, as shown and described.

DESCRIPTION

FIG. 1 is an isometric view of a sweatshirt with TV watch showing my new design;

FIG. 2 is a plan view thereof;

FIG. 3 is a front elevation view thereof;

FIG. 4 is a right side view thereof;

FIG. 5 is a left side view thereof;

FIG. 6 is a rear elevation view thereof;

FIG. 7 is a bottom plan view thereof; and,

FIG. 8 is an enlarged view of the TV watch of the sweatshirt with TV watch of FIG. 1.

The evenly spaced broken lines shown in the drawings depict portions of the sweatshirt with a TV watch that form no part of the claimed design. The dash-dash-line in the drawings represent the boundaries of the claim that form no part of the claimed design.
